DESIGN FOR A SHIP CLOCK

Abraham Levy and Joseph F. Punzak, Brooklyn, N. Y., assignors to United Metal Goods Manufacturing Co. Inc., Brooklyn, N. Y., a corporation of New York

Application September 19, 1940, Serial No. 95,214

Term of patent 3½ years

To all whom it may concern:

Be it known that we, Abraham Levy, a citizen of the United States, residing at Brooklyn, in the county of Kings and State of New York, and Joseph F. Punzak, a citizen of the United States, residing at Brooklyn, in the county of Kings and State of New York, have invented a new, original, and ornamental Design for a Ship Clock, of which the following is a specification, reference being had to the accompanying drawing, forming part thereof.

Figure 1 is a top plan view of the ship clock showing our new design;

Figure 2 is an end view looking toward the bow end of the ship; and

Figure 3 is a side elevation.

We claim:

The ornamental design for a ship clock, as shown,

ABRAHAM LEVY.
JOSEPH F. PUNZAK.
